UNITED STATES PATENT OFFICE.

FRANK A. RYDER, OF CHICAGO, ILLINOIS.

SPARK GAP.

Application filed November 18, 1921. Serial No. 516,068.

To all whom it may concern:

Be it known that I, FRANK A. RYDER, a citizen of the United States, and a resident of the city of Chicago, county of Cook, and 5 State of Illinois, have invented certain new and useful Improvements in Spark Gaps, of which the following is a specification.

My invention relates to improvements in spark gaps, especially adapted for use in 10 conjunction with internal combustion engines, and has for its object the provision of an improved construction of this character greatly facilitating the operation of said engines.

15 Other objects will appear hereinafter.

The invention consists in the combinations and arrangements of parts hereinafter described and claimed.

The invention will be best understood by 20 reference to the accompanying drawings forming a part of this specification, and in which,

Fig. 1 is a side view of a spark intensifier embodying the invention,

25 Figs. 2, 3, 4, and 5 are detail views of the different plates going to make up the body of the intensifier illustrated in Fig. 1,

Fig. 6 is a section taken on line 6—6 of Fig. 1,

30 Fig. 7 is a view similar to Fig. 6, but showing a modified form of construction,

Fig. 8 is a view of a spark plug and intensifier operatively connected together and each equipped with a spark gap embodying 35 the invention,

Fig. 9 is an enlarged bottom plan view of the spark plug, and

Fig. 10 is a detail view of one of the two electrodes illustrated in Fig. 6.

40 The form of construction illustrated in Figs. 1 to 6 inclusive, comprises two similar metallic electrodes 11 each provided at one end with an attaching ring 12 and at the other end with a terminal 13 turned per-

45 pendicularly thereto as shown. The electrodes 11 are arranged in a body plate 14 of the same thickness and as indicated in Fig. 6, the body plate 14 is provided with circular openings 15 to receive the rings 12 and

50 with a central chamber 16 connected by passages with the openings 15 to receive the electrodes and their terminals as shown. By this arrangement, when the electrodes are arranged in position in the plate 14, their

55 terminals are overlapped and arranged sub-

stantially parallel to each other, the end of each terminal being arranged adjacent the body of the other electrode and at the same distance therefrom as between said terminals, and whereby a substantially Z-shaped tortuous spark gap of uniform width is provided.

A bottom plate 17 of insulating material provided with openings to register with the openings 15 is arranged against the underside of body plate 14 and the spacer plate 18 of insulating material and also provided with openings to register with the openings 15 and with a central opening 19 to register with the spark gap is arranged against the upper side of plate 14. The cover plate 20 also of insulating material, is arranged over the plate 18 and is provided with a plurality of minute openings 21 positioned over the opening 19 and through which the spark crossing the spark gap may be observed. The parts are secured together by means of metallic eyelets or tubular rivets 22 passed through the ends thereof as shown and upset to secure the parts in place. By this arrangement a simple, economical and compact construction is provided which may be attached to any ordinary spark plug of an ordinary explosive or internal combustion engine and will serve to greatly intensify and "fatten" the spark, thus greatly increasing the efficiency and reliability thereof.

In Fig. 8, I have illustrated the intensifier above described as attached to a spark plug 23 and having the electrical conductor or supply wire 24 in turn attached to the intensifier, by means of a screw bolt 25 as shown. The electrodes 26 and 26' of the spark plug 23 have their terminals 27 turned perpendicularly thereto and overlapped and positioned to form a spark gap the same as that already described and as illustrated in Fig. 9, whereby the intensifying effect of the intensifier is increased.

In the modified form of construction illustrated in Fig. 7, the electrodes 28 are embedded in a solid block 29 of insulating material, and have their terminals 13 turned perpendicularly and arranged to form the spark gap as shown, the stems of said electrodes being additionally bent as shown to increase the length of the spark gap and to render the construction symmetrical. The electrodes 28 are provided with the attaching rings 12 projecting laterally from each

side of the body 29 and whereby the intensifier may be readily attached to a spark plug. By this arrangement a very simple and economical construction may be provided.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A spark gap comprising electrodes having their terminals turned substantially perpendicularly thereto, said terminals being overlapped and arranged substantially parallel to each other, substantially as described.
2. A spark gap comprising electrodes having their terminals turned substantially perpendicularly thereto, said terminals being overlapped and arranged substantially parallel to each other, the end of each terminal being arranged adjacent the body of the other electrode, substantially as described.
3. A spark gap comprising electrodes having their terminals turned substantially perpendicularly thereto, said terminals being overlapped and arranged substantially parallel to each other, the end of each terminal being arranged adjacent the body of the

other electrode and at the same distance therefrom as between said terminals, substantially as described.

4. A spark gap comprising electrodes having their terminals turned substantially perpendicularly thereto, said terminals being overlapped and arranged substantially parallel to each other; and a casing of insulating material enclosing said terminals, substantially as described.

5. A spark gap comprising electrodes having their terminals turned substantially perpendicularly thereto, said terminals being overlapped and arranged substantially parallel to each other, the end of each terminal being arranged adjacent the body of the other electrode; and a casing of insulating material enclosing said terminals, substantially as described.

6. A spark gap comprising electrodes having their terminals turned substantially perpendicularly thereof, said terminals being overlapped and arranged substantially parallel to each other, the end of each terminal being arranged adjacent the body of the other electrode and at the same distance therefrom as between said terminals; and a casing of insulating material enclosing said terminals, substantially as described.

In testimony whereof I have signed my name to this specification in the presence of two subscribing witnesses.

FRANK A. RYDER.
